DESIGN FOR AN AUTOMOBILE

Walter Dorwin Teague and Walter Dorwin
Teague, Jr., New York, N. Y.

Application November 7, 1938, Serial No. 80,918

Term of patent 7 years

To all whom it may concern:

Be it known that we, Walter Dorwin Teague and Walter Dorwin Teague, Jr., citizens of the United States, residing at 435 East 52nd Street, New York, N. Y., and 401 East 58th Street, New York, N. Y., respectively, have invented a new, original, and ornamental Design for an Automobile, of which the following is a specification, reference being had to the accompanying drawing, forming part thereof.

Figure 1 is a side elevational view, Figure 2 is a top plan view, and Figure 3 is a perspective view in elevation of an automobile showing our new design.

We claim:

The ornamental design for an automobile, substantially as shown.

WALTER DORWIN TEAGUE.
WALTER D. TEAGUE, JR.
